UNITED STATES PATENT OFFICE.

KAMETARO URAKAWA, OF SEATTLE, WASHINGTON.

CAN-OPENER.

1,168,979.

Specification of Letters Patent. Patented Jan. 18, 1916.

Application filed August 18, 1915. Serial No. 46,170.

To all whom it may concern:

Be it known that I, KAMETARO URAKAWA, a subject of the Emperor of Japan, residing at Seattle, in the county of King and State of Washington, have invented certain new and useful Improvements in Can-Openers, and do hereby declare the following to be a full, clear, and exact description of the invention, such as will enable others skilled in the art to which it appertains to make and use the same.

This invention relates to can openers, and has for an object to provide an opener which will cut a complete circle from the top of a can by depressing a handle.

A further object of the invention is to provide a can opener embodying means for embracing and engaging the top of a can and remaining stationary therewith, positioned and proportioned to cut a complete circle out of a can top actuated by depressing a handle member.

With these and other objects in view the invention consists in certain novel features of construction, combination and arrangement of parts as will be hereinafter more fully described and claimed.

In the drawings: Figure 1 is a diametrical sectional view of the improved can opener, certain parts being shown in side elevation broken away. Fig. 2 is a top plan view of the supporting bars and their adjusting means as indicated by arrow 2 at Fig. 1. Fig. 3 is a top plan view of the cutter bars taken on line 3—3 of Fig. 1. Fig. 4 is an end view of the supporting bars as indicated by arrow 4 at Fig. 1. Fig. 5 is an end view of the cutter bars and their knives as indicated by arrow 5 at Fig. 3. Fig. 6 is a transverse sectional view through the supporting bars taken on line 6—6 of Fig. 2. Fig. 7 is a transverse sectional view through the cutter bars taken on line 7—7 of Fig. 3. Fig. 8 is a detail of the drum on line 8 of Fig. 1.

Like characters of reference designate corresponding parts throughout the several views.

The improved can opener which forms the subject-matter of this application comprises a body 10 having vertical grooves 11 and 12 formed therein. Sliding in the grooves is an inverted U-shaped frame 13, carrying at its upper end a handle 14 and held resiliently at its upper extreme of movement by springs 15 and 16. The lower ends of the

frame 13 are turned inwardly to form lugs 17 and 18 moving respectively in spiral grooves 19 and 20 formed about the periphery of cylinder 21 which is rigid upon shaft 22.

Slidably mounted in the body 10 are horizontal supporting bars 23 and 24 retained in parallelism by keepers 25. The inner edges of the bars 23 and 24 are provided with rack teeth 26. The rack teeth 26 intermesh with the teeth of the pinion 27 mounted free to rotate upon the shaft 22. At their opposite ends the bars 23 and 24 carry supporting members or legs 28 of general S-shape, having oppositely opening slots 41, 42 formed in their sides and notches 29 formed in their lower ends to engage upon the bead at the periphery of the usual and ordinary tin can. It will be obvious that by moving the bars 23 and 24 the position of the supporting members 28 may be varied to engage the bead of a can of any desired diameter, and having once engaged such bead they will be retained thereby in such adjusted position. The adjustment of the bars 23 and 24 is accomplished manually by grasping the extended ends of such bars as shown at Fig. 1. Upon the lower end of the shaft 22 a drum 30 is fixed having horizontal openings 31 and 32 entirely therethrough as shown at Fig. 8, such openings being in parallelism with, but offset upon opposite sides of the diameter of said drum. Through the openings 31 and 32 cutter bars 33 and 34 respectively are slidably inserted, the latter being below the former but in parallelism therewith and retained in such parallelism by keepers 35. The bars 33 and 34 are also provided upon their inner surfaces with rack teeth 36 intermeshing with pinion 37 also mounted free to rotate upon the shaft 22.

One of the keepers 35 is provided with a set screw 38 by which the adjusted position of the parallel cutter bars 33 and 34 may be retained. It will be noted especially at Fig. 1 that the face of the pinion 37 is wide enough to engage both of the bars 33 and 34.

The bars 33 and 34 carry respectively cutting knives 39 and 40 which are capable of being set to cut a slit the desired distance from the periphery of the head by moving the bars 33 and 34 relative to each other and binding them in such position by the set screw 38.

In normal position the extended end of the bar 34 rests in the slot 41 in one leg 28 while the extended end of the bar 33 rests in the slot 42 in the other. When the device has been rotated one-half a revolution the shape of the legs permits the extended ends to move beyond the original position so that the cutting knives 39 and 40 may describe slightly more than half a circle to completely sever the circumscribed disk.

It will be obvious that as the drum 30 is rigidly attached to the shaft 22 to which is also rigidly attached the cylinder, when the latter is rotated by depressing the handle 14 the drum 30 will also be rotated to carry the cutting bars and their depending knives therewith to sever the disk from the top of the can as described.

It is believed that the operation of the device will be clearly understood from the foregoing description of its construction.

I claim:—

1. In a can opener, an upright shaft having fast on its lower end a drum provided with parallel openings through it on opposite sides of its center and at different heights, and means for rotating said shaft at will; combined with parallel rack bars slidable through said openings, a long pinion loose on the shaft within the drum and engaging the teeth of both bars, and a knife depending from one end of each bar for the purpose set forth.

2. In a can opener, an upright shaft having fast on it a drum provided with parallel openings through it on opposite sides of its center, and means for rotating said shaft at will; combined with parallel rack bars slidable through said openings, a pinion within the drum and engaging the teeth of both bars, a keeper near one end of each bar through which the other bar slides, a set screw in one keeper for engaging the bar within it, and a knife depending from one end of each bar for the purpose set forth.

3. In a can opener, a body, racks slidable substantially diametrically relative to the body and provided at their opposite ends with supporting members, a pinion interposed between the racks whereby the racks move in unison, other bars substantially diametrical relative to the body and provided with racks, a pinion interposed between the racks, cutters carried at the extremities of

the bars, a member attached to the cutter 55 bars and provided with spiral slots, and a frame movable vertically having lugs engaging in the spiral slots.

4. In a can opener, a body, racks slidable substantially diametrically relative to the body, a pinion interposed between the bars engaging the racks, supports carried at the extremities of the bars and provided with means for engaging the peripheral bead of a can, other bars slidable substantially diametrically relative to the body and provided at their opposite ends with cutters, a pinion interposed between the racks and interengaging therewith, a cylinder rigidly connected with the latter-mentioned bars and provided with circumferential spiral grooves, a frame slidable vertically relative to the body, and lugs carried by the vertically sliding frame engaging in the spiral grooves.

5. In a can opener, a body having opposite vertical grooves, a frame slidable in said grooves and having inturned lugs, an upright shaft journaled in said body, and a cylinder fast on the shaft and having spiral grooves engaged by said lugs; combined with a support carried by said body, a drum fast on the lower end of the shaft, rack bars passing transversely through the drum and having depending knives at their outer ends, and means for permitting the simultaneous longitudinal movement of said bars.

6. In a can opener, a body, an upright shaft journaled therein, means for rotating it at will, a pinion loose on the shaft, and a support comprising parallel rack bars guided horizontally through said body with their teeth engaging opposite sides of said pinion and downturned legs on opposite ends of opposite bars, each leg having side slots opening in opposite directions; combined with a drum fast on the shaft beneath said pinion and having transverse openings at different heights, a pair of rack bars slidable mounted through said openings and each having a short end with a knife depending from it and a long end lying normally in one of the slots in one of said legs, and a pinion loose on the shaft within the drum and engaging the teeth of the last-named bars, for the purpose set forth.

In testimony whereof I affix my signature.

KAMETARO URAKAWA.
